UNITED STATES PATENT OFFICE.

ROBERT S. BUSH, OF GREENSBURG, PENNSYLVANIA.

SWITCH-LEVER LOCK.

SPECIFICATION forming part of Letters Patent No. 608,833, dated August 9, 1898.

Application filed February 4, 1898. Serial No. 669,072. (No model.)

To all whom it may concern:

Be it known that I, ROBERT S. BUSH, a citizen of the United States of America, residing at Greensburg, in the county of Westmoreland and State of Pennsylvania, have invented certain new and useful Improvements in Switch-Lever Locks, of which the following is a specification, reference being had therein to the accompanying drawings.

10 This invention relates to certain new and useful improvements in switch-keepers, and has for its object to provide novel and effective means whereby a switch-lever, such as is employed in connection with railroad switches, may be automatically locked when it is moved to either of its respective positions and retained without the aid of the usual padlock.

15 The principal features of my invention comprise a pivoted locking-plate which projects through a suitable casing and which is adapted to be compressed within the casing by the action of a lever engaging the same and which when the lever passes beyond the 20 lower end of the same extends outwardly over the lever, requiring the releasing of the locking-bar and the withdrawal of the locking-plate within its casing, the latter being accomplished by means of the foot lever or 25 treadle.

30 In describing the invention in detail reference is had to the accompanying drawings, forming a part of this specification, and wherein like letters of reference indicate similar parts throughout the several views, in which—

35 Figure 1 is a perspective view of a portion of the switch, showing my improved keeper in position. Fig. 2 is a side view of the keeper. Fig. 3 is a longitudinal sectional view. Fig. 4 is a like view with the locking-plate removed. Fig. 5 is a rear view. Fig. 6 is a perspective view showing the front of the keeper. Fig. 7 is a like view showing the rear of the keeper with the plate removed. Fig. 8 is a perspective view of the locking-plate and levers for 40 operating the same. Fig. 9 is a rear view of a slightly-modified form of keeper. Fig. 10 is a perspective view of the locking-bolt.

45 Referring to the drawings by reference-letters, *a* indicates the bed-plate, which is firmly spoked or otherwise secured to the switch-tie *b* and which is provided at its one end with

an upwardly-extending lug *c*, which acts as a stop for the locking-plate *d*. This latter is pivotally hung upon a rod *e*, extending through 55 the block *f*, the latter being provided with a recess *f'*, within which the locking-plate is adapted to be depressed by the action of the switch-lever. This locking-plate *d* is pivotally secured within the recess by means of 60 the rod or pin *e*, extending through the block and through the upper left-hand corner of the locking-plate, thereby causing the one edge and lower portion of the plate to protrude through the recess and come into engagement 65 with the stop *c*. The lower edge of the locking-plate is cut on an incline, so that when the plate is in its normal or locking position the said lower edge will be on a horizontal line. This locking-plate is also provided with 70 a cut-away portion *d'*, which extends for some distance into the plate and within which is pivotally secured the rod *d*², likewise pivotally connected at its lower end to the foot or treadle lever *d*³, which has a bifurcated end 75 to receive the end of the rod *d*². This foot or treadle lever *d*³ is pivotally supported at its center, and by reason of the weight of the rod *d*² and a pull exerted on the same by the locking-plate *d* the outer end of the 80 foot or treadle lever is held normally elevated and is held depressible within a slot provided therefor in the plate *a* and in the plate *a'*, which is formed integral with the block *f* and forms a means for securing the 85 block to the plate *a*. A face-plate *a*² is secured to the rear of the block and prevents tampering with the locking-plate, said face-plate being provided with a keyhole, which registers with the aperture *a*³, provided in the 90 block *f*. Arranged within this block *f* is a sliding bolt or bar *g*, which is provided with a slot or groove *g'*, that is adapted to be engaged by the key inserted through the key-hole, and by means of the key this locking 95 bolt or bar may be thrust outwardly over the top of the locking-plate, and thereby prevent the moving of the same, or, when the bolt is withdrawn, the plate will be easily depressible within its block by the pressure of the 100 foot upon the treadle-lever *d*³.

In Fig. 9 of the drawings I have shown a lever *h*, pivotally hung within the block and having an upwardly-projecting end *h*², which

engages the groove or slot in the locking-bar when this bar is withdrawn to permit the operation of the plate and holds the same out of engagement with the said locking-bar.

5 When, however, this lever is operated, so as to release it from engagement with the bar, a coil-spring h^3 , arranged within the recess which contains the locking bar or bolt, forces the latter outwardly over the locking-plate 10 and prevents the operation of the same.

It will be observed that when this locking bar or bolt has been withdrawn the locking-plate d may be readily depressed within the recess in the block by a pressure on the foot 15 or treadle lever d^3 , and the switch-lever can then be turned from the position in which it has been locked to the opposite, the locking-plate d on the opposite keeper being depressed by the action of the lever as it comes into contact with the same until the lever passes out 20 of engagement with the said plate, which assuming its normal position locks the same within the keeper.

While the foregoing appears to embody the 25 preferred form of my invention, yet I do not wish to limit myself to the exact construction as herein shown and described, as various changes may be made in the details of construction without departing from the general spirit of my invention.

Having fully described my invention, what I claim as new, and desire to secure by Letters Patent, is—

1. In a switch-keeper the combination with

the bed-plate which is provided with an upwardly-extending lug forming a stop, a block on said plate, said block being provided with a recess in which is pivotally hung a locking-plate which normally protrudes through the recess in the block and engages the stop on 40 the plate, a treadle-lever connected to said locking-plate for withdrawing the same within the recess of the block, and a locking bolt or bar for engagement with the upper end of the locking-plate, substantially as shown and 45 described.

2. In a switch-keeper, the combination of the bed-plate which is provided with an upwardly-extending lug forming a stop, a block upon said plate, said block being provided 50 with a recess within which is pivotally hung a locking-plate which normally protrudes through the recess of the block and engages the stop of the plate, a foot or treadle lever pivotally hung within the block and connected by a pivoted lever to the locking-plate for operating the same, a locking bolt or bar arranged within the block and means for operating the same to engage with or disengage from the locking-plate, substantially as shown 55 and described.

In testimony whereof I affix my signature in the presence of two witnesses.

ROBERT S. BUSH.
